UNITED STATES PATENT OFFICE.

ROBERT J. RIORDAN AND JOSEPH P. HANLEY, OF CHICAGO, ILLINOIS; SAID RIORDAN
ASSIGNOR TO SAID HANLEY.

GARMENT-DISPLAY RACK.

Application filed January 9, 1920. Serial No. 350,388.

To all whom it may concern:

Be it known that we, ROBERT J. RIORDAN and JOSEPH P. HANLEY, citizens of the United States, residing at Chicago, in the county of Cook and State of Illinois, have invented a certain new and useful Improvement 5 in Garment-Display Racks, of which the following is a full, clear, concise, and exact description, reference being had to the accompanying drawings, forming a part of this specification.

The invention relates to garment display racks, and has among its various objects the provision of a simple and inexpensive construction 15 which will be efficient in operation and which will advantageously display a garment, yet will permit same to be collapsed with the garment thereon, so that the rack and garment may be stored away until 20 the garment is again to be displayed.

It is a further object of the invention to provide a structure which will automatically cause certain elements of the rack to be extended and collapsed when the garment is 25 to be displayed or arranged to be stored away.

It is a further object of the invention to provide shoulder portions which are also collapsible and which may be positioned so 30 as to lock other portions of the rack against accidental separation.

The invention has these and other objects, all of which will be more readily understood when read in conjunction with the accompanying drawings which disclose one embodiment thereof, and which will be explained in detail, and in which—

Fig. 1 is a perspective view of a rack constructed according to the invention in the 40 extended form;

Fig. 2 is an elevation of the rack showing the same collapsed;

Fig. 3 is a section taken on line 3—3 of Fig. 1; and

Fig. 4 is a detail view of a structure which 45 may be resorted to to provide the proper contour to the portion forming the shoulders of the rack.

In the embodiment of the invention as illustrated in the drawings the use of a main frame 10 is contemplated, which includes the upper frame 11, the lower frame 12 and the support 13, these being hingedly connected together as at 14 so that these portions 50 may be folded one upon the other so

as not to consume any more space than necessary when not on display, and to be extended when the garment is to be displayed. These frames are preferably formed of wire and formed or bent to produce the neck portion 60 15, the shoulder portion 16 and the hip portion 17, so that this portion of the device will simulate the outlines of body when viewed from the front. The portion 11 is provided with a plurality of spacer bars 18, which also 65 reinforce the device, being extended across the frame 11, and conveniently provide supports for the pivoted members 19, which preferably extend forwardly and rearwardly relatively to the frame 10. These members 19 70 decrease in dimension downwardly from the shoulders to about the hips where they again increase in dimension and cause these portions of the rack to simulate the outlines of the body when viewed from the side. The 75 lower frame 12 is provided with spacer bars 20 which extend between the downwardly extending members 12^a—12^b of the portion 12, and also carry elements 19. The elements 19 are each connected together by the 80 links 21—21 which are hingedly connected to these portions so as to permit same to be moved together when the main frames are collapsed or extended. A chain portion 22 extends from the uppermost element 19 to 85 the part 23 where it is securely fastened. Another chain portion 24 extends from the lowermost element 19 downwardly through the loop 20^a and has its opposite end secured at 25 to the element 26 of the support 13. 90

Another chain portion 27 extends from the support 13 to the rearwardly extending portion of the uppermost element 19. These chain and link connections provide the means for automatically causing the elements 19 to all assume a position which is transverse to the main frame when the support is moved to support the rack, and to display a garment. This arrangement will automatically cause the elements 19 to assume a position which is substantially parallel to the main frames when the support 13 is moved inwardly and will also allow the support 13 and the portion 12 to be folded upon the part 11. The main frames 11 and 12 are each provided with a holding means 28 for holding these elements in extended position, yet will permit them to be collapsed and to assume the position shown in Fig. 2. The upper portion 11 is provided 100 105 110

at the extremity of the shoulders with the semi-circular hinged elements 29—29, which are hinged so as to permit them to assume the position shown in Fig. 1, in which they add to the shape of the shoulders, and to permit them to be swung inwardly so that they will engage the uppermost one of the elements 19 and hold this portion close to the main frame when same is collapsed. It is evident that these last mentioned portions will automatically be caused to assume the position shown in Fig. 1 when the uppermost of the elements is brought to its transverse position upon the extension of the support 13.

Other collapsible elements 30 extend from the neck portion to the element 29. These elements 30 are also hingedly connected to the main frame and to the uppermost element 19 by the links 31 which are connected to the front and rear portions of the uppermost element 19. Thus this portion will be swung into and out of position each time the rack as a whole is positioned for display or storage.

From the foregoing explanation of the structure it is evident that when the support 13 is moved inwardly towards the frame that the forward portion of the element 19 will be swung upwardly substantially parallel to the main frame by chain section 27 which is fastened to the rearmost portion of these elements, and thus will cause the portions 30 to also swing substantially parallel with the main frame, and by virtue of the fact that the remaining elements are connected to this element 19 and together by the links 21, that these will also be caused to assume a similar position. When the parts are in this condition the lowermost portion 12 and the support 13 may be folded upon the portion 11 providing a compact structure which will not consume any extraordinary space when stored. The semi-circular portions 29—29 will then be swung inwardly to engage the uppermost element 19 to hold it. When a garment is desired to be displayed the portions 12 and 13 are unfolded, and as the support is moved rearwardly to a position to support the rack a pulling strain is exerted upon the chain 24 which will cause the forward portion of the elements 19 to be pulled downwardly to a position in which they are transverse to the main frame 11. The fact that the chain section 22 is secured to the element 23 of the main frame and to the uppermost and similar elements 19 which are connected together by the links 21, and the chain 24 is connected to the lowermost element will limit the rearward movement of the support 13. This will cause the elements 19 and the various other parts to be held in their proper position to display the garment when the parts are extended.

From the foregoing explanation of the construction and operation of the device it is evident that a simple and effective arrangement is produced whereby the various elements may be moved to extended or collapsed position to display a garment, and may be easily collapsed and reduced in dimension so as not to require any great space while being stored.

Having thus described one embodiment of the invention, it is obvious that changes and modifications may be resorted to without departing from the invention as expressed in the appended claims.

What we claim and desire to cover by Letters Patent is:

1. In a garment display rack the combination of a pair of main frames, connected together to permit same to be collapsed and extended, a plurality of supplemental frames secured to one of said main frames, a support for the main frames, said support also being collapsible, and extensible, and means connecting said support and supplemental frames whereby said supplemental frames are collapsed and extended when said support is collapsed or extended.

2. In a garment display rack the combination of a main frame composed of portions which are connected together and which may be collapsed and extended, supplemental frames secured to said main frame said supplemental frames being constructed to be collapsed and extended, and automatic means for actuating said supplemental frames when the main frame is collapsed or extended.

3. In a garment display rack the combination of a main frame, supplemental collapsible frames secured thereto, a support adapted to be arranged at an angle to the main frame to support the main frame and being movable to a position which is substantially parallel to the main frame, connections between said support and the supplemental frames whereby the supplemental frames are moved transversely and substantially parallel to the main frame upon the movement of the support to and from supporting position.

4. In a garment display rack the combination of a main frame, a plurality of supplemental frames secured thereto and constructed to be arranged substantially parallel and transversely to the main frame, one of said supplemental frames being extended upon the opposite sides of the main frame, a support for the main frame, and means connected to all of the supplemental frames and the support for automatically causing the supplemental frames to be arranged substantially parallel and transversely to the main frame.

5. In a garment display rack the combination of a main frame, a plurality of sup-

plemental frames secured thereto and constructed to be arranged substantially parallel with the main frame and transversely thereto, one of said supplemental frames extending upon opposite sides of the main frame, a support for the main frame and means connected with the support and said supplemental frame which extends upon opposite sides of the main frame for automatically causing the supplemental frames to be arranged substantially parallel and transversely to the main frame.

6. In a garment display rack the combination of a main frame, a plurality of supplemental frames secured thereto and constructed to be arranged substantially parallel and transversely to the main frame, one of said supplemental frames having portions which extend towards the opposite sides of the main frame, a support for the main frame and means connected with the support and said supplemental frame which extends towards the opposite sides of the

main frame for automatically causing the supplemental frames to be arranged substantially parallel and transversely to the main frame, said means being connected to a stationary portion of the main frame. 25

7. In a garment display rack the combination of a main frame, supplemental frames secured thereto and constructed to be arranged substantially parallel with the main frame and transversely thereto, one of said supplemental frames extending upon opposite sides of the main frame, a support for 30 the main frame and means connected with the support and said supplemental frame for automatically causing the supplemental frames to be arranged substantially parallel and transversely to the main frame. 35

In witness whereof, we hereunto subscribe our names this 29th day of November, A. D., 1919.

ROBERT J. RIORDAN.
JOSEPH P. HANLEY.
